Primary Examiner — April Rivas(74) *Attorney, Agent, or Firm* — Jones Day(57) **CLAIM**

The ornamental design for a case, as shown and described.

DESCRIPTION

FIG. 1 is a perspective view of a new design for a case, in a closed position;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a perspective view of a new design for a case, in an open position;

FIG. 9 is a front elevational view thereof;

FIG. 10 is a top plan view thereof; and,

FIG. 11 is a right side elevational view thereof.

The broken lines illustrate portions of the case that form no part of the claimed design.

1 Claim, 11 Drawing Sheets(56)
